Attest:

UNITED STATES PATENT OFFICE

CARL G. OLSON, OF CHICAGO, ILLINOIS, ASSIGNOR TO SHAKEPROOF LOCK WASHER COMPANY, OF CHICAGO, ILLINOIS, A CORPORATION OF DELAWARE

LOCK WASHER

Application filed August 7, 1930. Serial No. 473,553.

My invention relates generally to lock washers but more particularly to lock washers of the type formed from flat spring stock and provided with a plurality of marginal work engaging teeth.

One of the objects of my present invention is to provide a lock washer of the pronged type in which the prongs are of such a construction as to reduce the possibility of tearing or distorting the stock at the roots of the prongs when said prongs are deflected out of the plane of the washer proper.

More specifically, my invention contemplates the provision of a lock washer having a plurality of marginal prongs extending from a body portion, said prongs being deflected out of the plane of the body portion, the degree of deflection gradually increasing from the root of the prong so as to prevent the tearing of the stock at that portion.

Still more specifically my invention contemplates the provision of a lock washer as above set forth in which a plurality of radial slots are provided along one margin thereof, said slots being rounded at their inner extremities whereby to enable the gradual deflecting of a tooth or prong out of the plane of the washer at the root thereof.

The foregoing and other objects and advantages will be apparent from the following detailed description when considered in connection with the accompanying drawings, wherein:

Figure 1 is a plan view of a lock washer constructed in accordance with the teachings of my invention; and

Figure 2 is a transverse sectional view thereof taken substantially along the line 2-2 of Figure 1.

Referring to the drawings more in detail, it will be seen that one embodiment of my invention includes a lock washer which I have designated generally by the numeral 10. This lock washer is formed from flat spring stock and includes an annular body portion 12 provided with a plurality of internal marginal prongs 14. Spaces of cut-outs 16 serve to separate these prongs and particular attention is directed to the arrangement of the

roots of the prongs adjacent the inner ends of the radial cut-outs.

It will be seen that I provide an arcuate or curved edge 18 which extends between adjacent prongs. By this arrangement I am able to deflect the radial edges of the prongs 14 out of the plane of the body portion 12 without tearing or otherwise disfiguring the stock at the roots of the prongs. In other words, in deflecting opposite radial edges of the prongs 14 so as to provide work engaging edges 20, I gradually increase the degree of deflection from the center portion of the curved edge 18 to a point opposite the straight side of the prong and from this point the prong is uniformly deflected so as to present the work engaging edges 20 which are spaced from the plane of the washer body and are disposed in substantial parallelism therewith.

It should be noted that the teeth or work engaging edges 18 are displaced out of the plane of the washer stock an amount which is less than the thickness of the stock. This degree of deflection is indicated by the space "A" positioned between the arrows shown in Figure 2. This space "A" obviously is less than the thickness of the washer stock. In other words, I find that in a lock washer of the type which forms the subject matter of my present invention, it is preferable to displace the washer teeth to the described degree in order to obtain increased locking efficiency.

From the foregoing it will be apparent that when lock washers are constructed in accordance with the teachings of my invention, the prongs thereof may be warped or deflected out of the plane of the washer stock without the slightest possibility of fracturing or tearing the stock at the point where the prongs connect with the body portion. This is of utmost importance in connection with the manufacture of lock washers of the present type because when the stock is torn or broken as a result of the forming operation in a punch press, the strength of the washer is materially reduced. While I have disclosed in the drawings a lock washer in which the oppositely disposed portions of the prongs pre-

sent parallel work engaging edges, it will be apparent that other types of locking edges or corners may be formed without departing from the spirit and scope of the present invention. In other words, the curved portions at the roots of the prongs serve with equal effectiveness to prevent stock fracture and tearing in connection with washers equipped with various types of locking prongs. It might be stated that the prongs proper are not deflected out of the plane of the washer stock, but only the edges thereof. These edges lie in parallel planes throughout the length of the prongs with the exception of the portions of said prongs positioned along the curved bottom or inner edges of the slots, where they are formed into a helix resembling a screw thread. In other words, the edge on one side of each slot helically joins the corresponding edge on the opposite side of said slot. Thus the semicircular bottom portions of the slots provide edges which are helically disposed and gradually blend with the work engaging edges 20, which lie in parallel planes spaced from the washer body.

The invention is hereby claimed as follows:

1. A lock washer of flat spring stock including an annular body portion and a plurality of prongs spaced along a margin thereof, said prongs being spaced by radial notches, the root portion of each prong being curved so that the curvature of one root blends into the curvature of the next adjacent root, marginal portions of said prongs being deflected out of the plane of the body portion so as to present oppositely disposed work engaging edges lying in planes spaced from and substantially parallel with the plane of the body portion, the edge forming a continuation of the cutting edge of each prong beginning at the root thereof and extending helically so as to blend with the marginal edge of the next adjacent prong at the root thereof, whereby to present a helical configuration which enables said edges to be deflected out of the plane of the washer stock without subjecting the portion thereof adjacent said roots to the possibility of fracture and whereby to increase the strength of the root of the prong for counteracting the tendency of the prong to flatten when clamped against a work piece.

2. A lock washer of flat spring stock including an annular body portion and a plurality of prongs spaced along one margin thereof, said prongs being spaced by radial notches, the root portion of each prong being curved so that the curvature of one root blends into the curvature of the next adjacent root, marginal portions of said prongs being deflected out of the plane of the body portion so as to present oppositely disposed work engaging edges lying in planes spaced from the body portion a distance less than the thickness of the stock and parallel with said body portion, the edge forming a continuation of the

cutting edge of each prong beginning at the root thereof and extending helically so as to blend with the marginal edge of the next adjacent prong at the root thereof, whereby to present a helical configuration which enables said edges to be deflected out of the plane of the washer stock without subjecting the portion thereof adjacent said roots to the possibility of fracture and whereby to increase the strength of the root of the prong for counteracting the tendency of the prong to flatten when clamped against a work piece.

In witness whereof, I have hereunto subscribed my name.
